UNITED STATES PATENT OFFICE.

EUGEN HAGENBUCHER, OF ESSEN, GERMANY, ASSIGNOR TO FRIED. KRUPP AKTIEN-GESELLSCHAFT, OF ESSEN-ON-THE-RUHR, GERMANY.

LOCOMOTIVE.

Application filed January 15, 1923. Serial No. 612,870.

To all whom it may concern:

Be it known that I, EUGEN HAGENBUCHER, residing at Essen, Germany, a citizen of the German Republic, have invented a certain 5 new and useful Improvement in Locomotives, of which the following is a specification.

This invention relates to locomotives of the kind comprising a blower for producing 10 an artificial draught, and it has for its object to provide a smoke box of a construction which will allow the firing of the locomotive boiler by natural draught or by means of an auxiliary blower also in case 15 the blower has been stopped, without interfering with the accessibility of the smoke tubes of the boiler.

The accompanying drawing illustrates, by way of example, an embodiment of the subject matter of the invention.

Fig. 1 is a longitudinal section through the smoke box,

Fig. 2 is a plan view corresponding to Fig. 1, and

Fig. 3 is a section on the line 3—3 of Fig. 2, seen from the left.

The smoke box which is divided by a partition *g* into two chambers *r* and *s*, possesses a main chimney *b* and an auxiliary chimney 30 *c* which is co-axially inserted into the main chimney and generally closed by a rotatable flap *d*.

The flue gases pass by the way 1, 2, 3 from the boiler *e* through an opening *f* of the partition *g* and the opening *h* of the smoke box into an economizer, not shown in the drawing, which is arranged laterally of the boiler *e*. A blower will cause the flue gases to pass from the economizer along the way 40 4, 5 either directly or indirectly after flowing through another economizer, by the opening *i* of the smoke box into the annular channel *o* of the smoke box and from the latter through the main chimney *b* into the atmosphere.

As is to be seen from Figs. 1 and 3, the partition *g* is connected by staybolts *m* to the smoke box door *k*, so that upon opening the smoke box door all smoke- and fire-tubes are freely accessible. The partition *g* may, of course, be also detachably connected to any other part of the smoke box.

If no steam is consumed, such as for instance when lighting-up or during the stoppage at the stations, the flap *d* is swung

down completely so that the auxiliary chimney *c* is open and the opening *f* of the partition *g* closed by the flap *d*. In this case, the flue gases can no longer pass to the main chimney *b* but are all driven out through the auxiliary chimney *c* by means of an auxiliary blower *p*.

Claims:

1. A locomotive comprising a blower for producing an artificial draught, a smoke box, a main chimney and an auxiliary chimney, the smoke box being divided into two chambers, one of these chambers being in communication with a channel leading to the main chimney and the other chamber being provided with means adapted to put this chamber in communication either with the first-mentioned chamber or with the auxiliary chimney.

2. A locomotive comprising a blower for producing an artificial draught, a smoke box, a main chimney and an auxiliary chimney, the smoke box being divided into two chambers, one of these chambers being in communication with a channel leading to the main chimney and the other chamber containing an auxiliary blower and being provided with means adapted to put this chamber in communication either with the first-mentioned chamber or with the auxiliary chimney.

3. A locomotive comprising a blower for producing an artificial draught, a smoke box, a main chimney and an auxiliary chimney, a partition in the smoke box, said partition being easily detachably connected to a part of the smoke box and arranged to divide the smoke box into two chambers, one of these chambers being in communication with a channel leading to the main chimney and the other chamber containing an auxiliary blower and being provided with means adapted to put this chamber in communication either with the first-mentioned chamber or with the auxiliary chimney.

4. A locomotive comprising a blower for producing an artificial draught, a smoke box, a main chimney and an auxiliary chimney, a partition in the smoke box arranged to divide the smoke box into two chambers, one of these chambers being in communication with the main chimney and the other chamber containing a blower and being in communication with the auxiliary chimney, an opening in the said partition for estab-

lishing communication between the two chambers, and a flap mounted for limited rotation in the smoke box and adapted, when in one limit position, to close the said opening of the partition and, when in its other limit position, to interrupt the communication between the last-mentioned chamber and the auxiliary chimney.

5. A locomotive comprising a blower for
10 producing an artificial draught, a smoke
box, a main chimney and an auxiliary chimney, a partition in the smoke box arranged
to divide the smoke box into two chambers,
an annular channel formed in the smoke box
5 for permitting the flue gases to pass into the
main chimney, one of the two smoke box
chambers being in communication with the

said annular channel and the other chamber
containing a blower and being in communica- 20
tion with the auxiliary chimney, an opening
in the said partition for establishing
communication between the two chambers,
and a flap mounted for limited rotation in
the smoke box and adapted, when in one
limit position, to close the said opening of 25
the partition and, when in its other limit position,
to interrupt the communication between
the last-mentioned chamber and the auxiliary chimney.

The foregoing specification signed at Co- 30
logne, Germany, this 9th day of December,
1922.

EUGEN HAGENBUCHER.
